[57] CLAIM

The ornamental design for an article of clothing, as shown and described.

DESCRIPTION

FIG. 1 is a front elevation view of an article of clothing showing my new design; and.

FIG. 2 is a front elevation view of the article of clothing illustrated in FIG. 1 with the outer garment unbuttoned.

The rear of the shirt and the portion of the bra top not disclosed in FIG. 2 of the article of clothing forms no part of the claimed design.
